UNITED STATES PATENT OFFICE

97,015

DESIGN FOR A TRISEAT AIRCRAFT CHAIR

Lewis C. McCarty, Jr., Towson, and Drew M. Helwig, Baltimore, Md., assignors to The Glenn L. Martin Company, Baltimore, Md.

Application October 5, 1934, Serial No. 53,499

Term of patent 7 years

To all whom it may concern:

Be it known that we, Lewis C. McCarty, Jr., and Drew M. Helwig, citizens of the United States and residents, respectively, of Towson, in the county of Baltimore and State of Maryland, and of Baltimore, in the State of Maryland, have invented a new, original, and ornamental Design for the Triseat Aircraft Chair, of which the following is a specification, reference being had to the accompanying drawing, forming part thereof.

Figure 1 is a front perspective view of the subject chair showing the triseat bracing, sectional-

ly upholstered individual sling seats with backs, and safety belts; one of the chair seats and backs being adjusted for a reclining person.

Figure 2 is a rear perspective view of the subject chair showing the triseat bracing, and individual sling backs; one of the chair seats and backs being adjusted for a reclining person.

We claim:

The ornamental design for a triseat aircraft chair substantially as shown and described.

LEWIS C. McCARTY, JR.
DREW M. HELWIG.
